A. B. Bowman

Attorney

UNITED STATES PATENT OFFICE

GLEN C. HOLBERT, OF SAN DIEGO, CALIFORNIA

PIPE STRAIGHTENING APPARATUS

Application filed December 2, 1931. Serial No. 578,534

My invention relates to pipe straightening apparatus, and the objects of my invention are:

First, to provide an apparatus of this class which is particularly adapted for straightening bent or twisted pipe but which is also adapted to straighten angle iron or structural iron with other cross sections:

Second, to provide an apparatus of this class which is particularly rugged and sturdy of construction adapted to withstand considerable abuse and be used in exposed places;

Third, to provide an apparatus of this class in which the force of the two clamping jaws on said apparatus increases as they approach each other:

Fourth, to provide an apparatus of this class in which one of the clamping jaws is provided with a slightly yieldable face which allows for the slight resiliency of the pipe or other material being straightened; and

other material being straightened; and
Fifth, to provide an apparatus of this class
which is durable, efficient in its action and
which will not readily deteriorate or get out
of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a plan view of my pipe straightening apparatus with parts and portions broken away to facilitate the illustration; Fig. 2 is a transverse sectional view thereof 40 through 2—2 of Fig. 1 with parts and portions shown in elevation to facilitate the illustration; Fig. 3 is a fragmentary sectional view through 3—3 of Fig. 1, and Fig. 4 is another fragmentary sectional view through 45 4—4 of Fig. 1, and Fig. 5 is a side view of a modified clamp jaw.

Similar characters of reference refer to similar parts and portions throughout the several views of the drawing.

50 Body frame 1, rails 2, wheels 3, axles 4,

carriage frame 5, guide member 6, driving screw 7, bearings 8, pinion gear 9, spur gear 10, motor 11, traveler members 12, link members 13, bracket 14, clamp jaw 15, and clamp jaw facing 16, constitute the principal parts and portions of my pipe straightening apparatus.

My apparatus includes a body frame 1 formed of two end members 1a connected by side members 1b secured to the upper sides 60 of said end members 1a at the extremities thereof. The end members 1a are also connected by means of rails 2 positioned inwardly and below the side members 1b. Mounted upon the rails 2 are wheels 3 which are connected in pairs by means of axles 4. 65

The wheels 3 are adapted to support the side members, designated 5a, of the carriage frame 5. Said carriage frame is rectangular and the side members 5a are disposed flush with the side members 1b of the body frame. The ends of the carriage side members 5a are connected by cross members 5b and 5c disposed above the side members 5a. Suitable braces 5d rigidly hold the cross members 5b and 5c. The carriage side members 5a are also connected by brace members 5e which extend diagonally. Secured to the under sides of the cross members 5b and 5c between the frame side members 1b with its upper surface flush therewith is a guide member 6.

A driving screw 7 extends across the body frame and carriage frame and is supported at its extremities by means of bearings 8 secured to the side members 1a. One end of the driving screw protrudes from its bearing 8 and is provided with a pinion gear 9 which is driven by a spur gear 10 which in turn is driven by a suitable motor 11. The driving screw 7 includes a righthanded threaded portion and a lefthanded threaded portion their inner extremities terminating at a centrally disposed stop 7a and their outer extremities terminating adjacent to the bearings 8. 95

95
Mounted upon the driving screw 7 are a pair of traveler members 12, each of which is provided with a pair of oppositely extending horizontally disposed ear portions 12a. Corresponding ends of a pair of link mem- 100

bers 13 are connected above and below each ear portion 12a. Four pairs of such link members are provided. The two pairs of link members on the side of the driving screw 5 facing the cross members 5b of the carriage frame extend towards each other and are connected at their adjacent ends to a common bracket 14 which is secured to and extends from the cross member 5b above the guide member 6.

The other two pairs of link members 13, disposed between the driving screw 7 and cross members 5c, extend towards each other and are connected at their adjacent ends to 15 a bearing lug 15a extending laterally outwardly from a clamp jaw 15. The clamp jaw is in the form of a rectangular block of material provided with a channel 15b in its lower side adapted to receive the guide member 6. The side of the clamp jaw 15 facing the cross member 5c forms one face of the pipe straightening clamp. The cross member 5c forms the other jaw of the clamp and the side thereof toward the clamp jaw 15 25 may be provided with a clamp jaw facing 16 in the form of a block of wood or other slightly yieldable material.

The face of the clamp jaw 15 is provided with a semi-cylindrical groove 15c which prevents the pipe from twisting out of the clamp jaw as well as preventing undue flattening thereof. When it is desired to straighten angle iron, the clamp jaw shown in Fig. 5 is used. This clamp jaw is similar to the above structure except that a slot 15d adapted to receive one angular portion of the angle iron is provided in place of the groove 15c.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

50. 1. In a pipe straightening apparatus, a rectangular fixed frame, a rectangular carriage frame reciprocally mounted in said fixed frame, including end portions protruding above said fixed frame, one of said end portions forming a clamp jaw, a second clamp jaw provided with a groove for receiving work, a screw member extending across said carriage frame and supported from said fixed frame, traveler members associated with said screw member, and links extending from each of said traveler members to said carriage frame and said second jaw.

60. 2. In a pipe straightening apparatus, a fixed frame, a carriage frame reciprocally supported thereby including a major clamp

jaw forming an end of said carriage and disposed above said fixed frame, and a single middle guide extending at right angles to said clamp jaw, a relatively narrow minor clamp jaw slidable upon said guide, its face being smaller than said major clamp jaw and disposed opposite the central portion thereof and provided with a work receiving groove in one side, and screw and link means supported from said fixed frame for simultaneously shifting said carriage in one direction and said minor clamp jaw in opposite direction.

3. In a pipe straightening apparatus, a fixed frame, a carriage frame reciprocally supported thereby including a major clamp jaw forming an end of said carriage and disposed above said fixed frame, and a guide extending at right angle to said clamp jaw, a minor clamp jaw slidable upon said guide and provided with a work receiving groove in one side, its face being smaller than said major clamp jaw and disposed opposite the central portion thereof, a screw member extending across said carriage frame and supported from said fixed frame, traveler members associated with said screw member, and links extending from each of said traveler members to said carriage frame and said second jaw.

4. In a pipe straightening apparatus, a fixed rectangular frame, a rectangular carriage frame reciprocally supported thereby provided with a major clamp jaw forming one end of said carriage and disposed above said fixed frame, wheels supporting said rectangular carriage, a guide secured to said carriage extending across the middle thereof longitudinally and at right angles to said major clamp jaw, a relatively narrow minor clamp jaw provided with a work receiving groove in the side facing said major clamp jaw slidable on said guide, a screw member extending across said carriage frame and supported from said fixed frame at its ends, traveler members associated with said screw member, and links extending from each of said traveler members on opposite sides of said screw member, the free ends of said links on one side connected with said minor jaw and the free ends of the other links connected with said carriage at the middle portion thereof, whereby said carriage is shifted in one direction and said minor clamp jaw is shifted in the opposite direction and said clamp jaws shifted towards each other.

5. In a pipe straightening apparatus, a fixed frame, a shiftable carriage frame, wheels upon which said shiftable carriage is supported, tracks therefor, a clamp jaw carried by said carriage frame extending laterally across said frame at one end, a second relatively narrow clamp jaw shiftable with respect to said carriage frame and first men-

tioned clamp jaw, and screw and link means for shifting said clamp jaws in opposite directions.

6. In a pipe straightening apparatus, a
5 fixed frame, a shiftable carriage frame,
wheels upon which said shiftable carriage is
supported, tracks therefor, a clamp jaw car-
ried by said carriage frame extending later-
ally across said frame at one end, a second
10 relatively narrow clamp jaw shiftable with
respect to said carriage frame, a screw mem-
ber extending across said carriage frame and
supported from said fixed frame, traveler
members associated with said screw member,
15 and links extending from each of said travel-
er members to said carriage frame and said
second jaw.

In testimony whereof, I have hereunto set
my hand at San Diego, California, this 12th
20 day of November, 1931.

GLEN C. HOLBERT.
